DESIGN FOR A DISPLAY STAND FOR GRINDING WHEELS AND SIMILAR ARTICLES

Edward B. Gallaher, Norwalk, Conn., assignor to
Clover Manufacturing Co., Norwalk, Conn., a
corporation of New York

Application April 27, 1945, Serial No. 119,277

Term of patent 14 years

(Cl. D80—9)

To all whom it may concern:

Be it known that I, Edward B. Gallaher, a citizen of the United States of America and a resident of Norwalk, Connecticut, have invented a new, original, and ornamental Design for a Display Stand for Grinding Wheels and Similar Articles, of which the following is a specification, reference being had to the accompanying drawing, forming part thereof,

Figure 1 is a front perspective view of the display stand showing my new design.

Figure 2 is a rear perspective view and

Figure 3 is a side view of the display stand.

I claim:

The ornamental design for a display stand for grinding wheels and similar articles, as shown.

EDWARD B. GALLAHER.
